BED HEADBOARD

Robert W. Stavely, Detroit, Mich.

Application August 20, 1948, Serial No. 148,220

Term of patent 14 years

(Cl. D5—4)

To all whom it may concern:

Be it known that I, Robert W. Stavely, a citizen of the United States, residing at Detroit, in the county of Wayne and State of Michigan, have invented a new, original, and ornamental Design for a Bed Headboard, of which the following is a specification, reference being had to the accompanying drawing, forming part thereof, wherein in Fig. 1 is a front elevation of a bed headboard embodying my new design, one of the legs being shown broken for convenience of illustration. Fig. 2 is a side elevation of the headboard of Fig. 1, and Fig. 3 is a fragmentary section taken on the line 3—3 of Fig. 1. The dominant features of the design reside in the portions illustrated in full lines.

I claim:

The ornamental design for a bed headboard, as shown and described.

ROBERT W. STAVELY.
